WINDOW

David R. Leahy, Schenectady, N. Y., assignor to
 American Locomotive Company, New York,
 N. Y., a corporation of New York

Application February 24, 1940, Serial No. 320,577

1 Claim. (Cl. 114—173)

This invention relates to windows adapted for use as deck house lights on a ship.

An object of the invention is to provide in a ship deck house, a side wall opening for outward horizontal vision and an aligned roof opening for vertical skyward vision, together with a window for closing the openings, formed of two sashes hinged together, the upper sash being swingable upwardly to close the roof opening and the lower sash being slideable upwardly to close the side wall opening, the upper sash being foldable upon the lower sash and the lower sash being slideable downwardly with the upper sash folded thereagainst to an out-of-the-way position below the side wall opening to entirely clear the openings.

Other and further objects of and advantages achieved by the invention will be apparent from the following description of an approved embodiment thereof.

In the accompanying drawings, Figure 1 is an inside elevation of a ship window embodying the present invention, the lower ends of the racks and tie bar of the window being indicated by dot and dash lines in their lowermost position; Fig. 2 is an end view of the window shown in Fig. 1 as viewed from the left, the deck house bulkhead and a part of the deck house roof with which the window is associated being shown in section, the window lateral movement mechanism lever being shown in its uppermost position in dot and dash lines and a transom partially-open position being indicated in dot and dash lines; Fig. 3 is a section of a portion of the parts shown in Fig. 1, taken on the line III—III of Fig. 1, the lower section and transom being shown in full lowered position with the transom folded abreast of the lower section; Fig. 4 is an enlarged fragmental section on the line IV—IV of Fig. 2, the window lower section being shown not pressed against its rubber sealing member and the transom being shown in dot and dash lines in its open position abreast of the window lower section; Fig. 5 is an enlarged fragmental section on the line V—V of Fig. 2, the transom being shown not pressed against its rubber sealing member, with the locking member turned 90 degrees from its position in Fig. 2; Fig. 6 is an enlarged fragmental section on the line VI—VI of Fig. 1, showing parts in dot and dash lines; Fig. 7 is an enlarged fragmental section on the line VII—VII of Fig. 1, the locking member being shown in open position in dot and dash lines; and Fig. 8 is an enlarged fragmental view of the hinge

connection between the window lower section and the transom.

The window of the present invention, indicated generally by the reference numeral 1, includes a main window section 2, which in the present embodiment is the lower section. This section, in the present embodiment, is similar to the window structure shown in the Rohman et al. Patent No. 1,962,328, June 12, 1934, except as modified 5 in accordance with the present invention to provide for an upper section or transom 3. It will be understood that the type of window of the patent has been chosen for use with the transom of the present invention merely because it lends 10 itself readily to such adaptation, but it is contemplated that other types of windows may also be employed if desired, and other uses made of the window than as a ship window.

The window structure is shown disposed in a 20 deck house 4 of a ship. The deck house bulkhead 5 is provided with an opening in which fits the lower part of a stationary window casing 6 for the window lower section, and the deck house roof 7 is provided with an 25 opening (a continuation of the bulkhead opening), in which fits the upper part of the casing 6, forming a frame for the upper window section or transom 3. The lower part of the casing is vertical and consists of a bottom horizontal member 8 and side members 9. The upper part of the 30 casing or transom frame is inclined inwardly of the deck house and consists of a top horizontal member 10 and oblique side members 11 secured at their bottom ends to the top ends of the 35 side members 9. The casing 6 is built up forming a unitary rigid structure.

The bottom member 8 consists of a horizontally extending flat bar 12 parallel to and secured to the bulkhead, a flange 13 extending outward over the lower edge of the bulkhead opening and a larger grooved flange 14 extending inwardly toward the window section 2, in the 40 groove of which is disposed a resilient rubber sealing member 15 against which the window section 2 is pressed when the window is in closed position.

Each side member 9 consists of a vertically extending flat portion 16 parallel to and secured to the bulkhead. A flange 17 extends outwardly from one side of the portion 16 over the adjacent edge of the bulkhead opening and a longer flange 18 extends inwardly toward the window section 2. The inner end of the flange 18 is enlarged and provided with a wedge-shaped 55 groove 19 in which is disposed a resilient rubber

sealing member 20. A supporting flange 21 extends inwardly from the opposite side of the portion 16, parallel to the flange 18. It extends, however, to the inner side of window section 2. A finishing strip 22 is secured by round-headed screws 23 to the inner edge of the flange 21 and extends in overlapping relation with the edge of the window section 2. The edge of the strip remote from the flange 21 is turned at right angles to the plane of the strip toward the window section for a purpose later to be mentioned. Other screws 23, but having their heads countersunk, secure the members 8 to 11 to the deck house.

The flange 21 is provided with three inclined slots 24, the slots slanting in an outward direction from bottom to top. Each of the slots is provided with a removable wedge member 25. Each wedge member includes an oblong plate 26 which is disposed on the deck house side of its respective flange 21 and secured thereto by screws 27 and a slanting wedge piece 28 integrally formed on the side of the plate 26 engaging the flange 21 and fitting into and extending through the slot 24 for a purpose later to be described.

The members 10 and 11 of the transom frame are made of the same frame section and therefore a description of one side member 11 as shown in Fig. 5 alone will be given. The member 11 consists of parts 29, 30, 31, 32, 33, 34 and 35 which are similar respectively to the parts 16 to 22 of the members 9. The flange 31 is, however, longer than the flange 18 as the transom 3 is spaced from the portion 29 further than the window section 2 is spaced from the portion 16.

There are three locking members indicated generally by the reference numeral 36, secured to the transom frame, one on each side and one at the top thereof. Each has a body portion 37 seating on the strip 35. An operating handle 38 extends in one direction from the body portion and a finger 39 extends from the body portion at right angles to the handle. The body portion has an unthreaded orifice 40 in line with a smaller unthreaded orifice 41 formed in the strip 35, a shoulder 42 being formed by the portion of the strip extending from the periphery of the orifice 41 to the periphery of the orifice 40. A boss 43 is formed integrally with or welded on the flange 34 opposite each body portion 37 and each boss contains a threaded orifice 44 in line with and the same size as the adjacent orifice 41. A screw 45 secures the body portion to the strip 35, the screw having a head 46 engaging the inner side of the body portion, an unthreaded portion 47 extending through the orifice 40 and a smaller threaded portion 48 extending through the orifice 41 and screwed into the threaded orifice 44. A shoulder 49 is provided on the screw between the unthreaded portion 47 and the smaller threaded portion 48 and this shoulder 49 fits against the shoulder 42. As the unthreaded portion 47 is slightly longer than the unthreaded orifice 40 the body portion has working clearance between the head 46 and the strip 35 and can be turned readily from operative to inoperative position.

The window section 2 consists of a pane of glass 50 held within a frame 51 consisting of a tie bar or bottom member 52, top member 53 and side members 54. The bottom member is merely a bar extending between and fastened to the side members and engaging the bottom edge of the pane 50. It may of course, if desired, be channel-

shaped to engage the sides of the bottom edge of the pane 50 also.

Each of the side members 54 has a body portion 55 which contains a channel 56 in which is disposed a rubber channel 57 in which the pane 50 is firmly held.

A toothed rack 58 extending the full length of the side member 54 is formed integrally with or secured to the inner side of the member 54 and a groove 59 facing in an opposite direction from the channel 56 is formed adjacent the outer side of the member 54, the rack 58 and groove 59 being for a purpose later to be mentioned.

The top member 53 consists of a body portion 60 which contains a channel 61 in which is disposed a rubber channel 62 which firmly holds the upper edge of the pane 50. The upper face of the member 53 contains a groove 63 in which is disposed a resilient rubber sealing member 64. Three spaced hinge lugs 65 are formed on the inner top portion of the member 53 for a purpose later to be described.

The upper section or transom 3 consists of a pane of glass 66 held within a frame 67 consisting of a top member 68, bottom member 69 and side members 70. The side and top members are made of simple channel irons, in the channels of which are disposed rubber channels 71 securely holding the adjacent edges of the pane 66. On the center of the inner side of the side and top members, at points adjacent the locking members 36, are formed or secured wedge members 72 providing cam surfaces for a purpose later to be described. The bottom member 69 consists of a channelled body portion 73 in the channel of which is disposed a rubber channel 74 securely holding the bottom edge of the pane 66.

Three spaced pairs of hinge members 75 extend downwardly from the inner bottom portion of the bottom member 69, one at each side of each lug to cooperate therewith to hinge the transom to the window section 2 for swinging movement relative thereto. The hinge lugs and members are connected together by pins 76. The bottom member 69 also has a portion 77 which functions to seal the joint between the transom and section 2. This portion 77, describing it when the transom is closed (the section 2 being then in its raised closed position), consists of a rounded outwardly and downwardly extending member 78 and a horizontal member 79 which extends outwardly from the bottom of the member 78. The member 79 is pressed against the resilient rubber sealing member 64 when the transom is in closed position so that no water or air can leak through the joint between the transom and section 2. A portion of each hinge member 75 is formed by the rounded member 78 and each hinge member 75 is strengthened by a reinforcing flange 80 which is connected at its upper end to the body portion 73, at its inner edge to the member 78, and at its lower edge to the member 79.

The window comprises a mechanism, indicated generally by the reference numeral 81, for positively raising and lowering the window, and a window lateral movement mechanism indicated generally by the reference numeral 82. They are enclosed within a common housing 83 which extends completely across the width of the window adjacent the bottom part thereof when the window is fully raised. A sheet of metal 84 depends from the bottom of the housing and, together with the housing, both of which are spaced from the inner side of the bulkhead, form a pocket 85 in which the window section 2 and transom are

disposed when in full lowered (window open) position.

The window raising and lowering mechanism comprises a horizontal shaft 86 extending longitudinally of the housing 83 and supported thereby by bearings 87 secured to the inner face of the housing. A worm wheel 88 is secured on the shaft and meshes with a worm 89 formed on a shaft 90 which extends at right angles to the shaft 86 and extends through the housing 83 into the interior of the deck house. An operating handle 91 is secured to the inner end of the shaft 90. On either end of the shaft 86 is secured a pinion 92 in mesh with the lower end of the adjacent rack 58 when window section 2 is closed. By rotating the handle 91 in one direction or another, the window is raised or lowered by the operation of the pinions 92 and racks 58.

The window lateral movement mechanism 82 comprises a shaft 93 above and parallel to the shaft 86, within the housing 83 and supported thereby by bearings 87 similar to the bearings 87. A handle 94 is secured to the shaft 93 and extends through the wall of the housing into the interior of the deck house. At each end of the shaft 93 is secured a gear segment 95 in mesh with an inclined toothed rack 96. Each rack 96 is inclined downwardly and inwardly and each segment 95 increases radially upwardly in order to permit coaction between the teeth of the segments and teeth of the racks.

The racks 96 are formed on vertical wedge bars 97, one of which is disposed at each side of the window section 2 between the adjacent flange 21 and side member 54. Each bar 97 has three inclined slots 98, each opposite one of the slots 24 and in each of which is disposed a wedge piece 28. A flange 99 extends from the outer side of the bar 97 at right angles thereto into the groove 59 thereby connecting the bars 97 each with the adjacent side member 54. The strip 22 encloses both the member 54 and bar 97.

The operation of the window lateral movement mechanism is as follows. When the window is in its full upper position and it is desired to press the window section 2 against the sealing member 20, the handle 94 is pushed downward, which moves the racks 96 upward and outward, forcing the bars 97 upward and because of the wedge pieces 28, outward. Movement of the bars 97 outward is accompanied by outward movement of the members 54 because of the flange and groove connection therebetween, thereby forcing the window section 2 into tight engagement with the sealing member 20.

When the window section 2 is in full upper position and it is desired to lock the transom, the lock members 36 (the transom first being closed) are each turned so that each finger 39 engages the cam surface of the adjacent wedge member 72, forcing the transom into tight engagement with the sealing members 33 and 64, the transom frame abutting the transom.

The advantages of the present invention are apparent from the foregoing description. With the window section 2 and transom in full raised position and forced into engagement with their respective rubber sealing members by the mem-

bers 36 and mechanism 82, no water or air can enter the deck house from the exterior. Added overhead or vertical visibility is afforded from the interior of the deck house, due to the inclined transom. The transom can be lowered to a position abreast of the window section 2 without disturbing the window in any way or it may be moved to some partially open position (when the window section is closed), as indicated in dot and dash lines in Fig. 2, and held there by any suitable means such as a chain (not shown). Furthermore, the window section 2 and transom can be lowered, when the transom is abreast of the window section 2, to any desired position between full upper and full lowered window position and held in this position by the worms 88 and 89. Finally the transom may be moved to an out-of-the-way position in the pocket with the window section 2 when full window opening is desired.

It will be obvious that the increased overhead view attained by means of the inclined transom is important in modern day ship building, especially in the case of war vessels where visibility is necessary in order to sight air-planes passing overhead. However, the invention is not limited to an inclined transom for, from various aspects thereof, it may be applied to a vertical transom hinged to a vertically slideable window section.

While there has been hereinbefore described an approved embodiment of this invention, it will be understood that many and various changes and modifications in form, arrangement of parts and details of construction thereof may be made without departing from the spirit of the invention and that all such changes and modifications as fall within the scope of the appended claim are contemplated as a part of this invention.

The invention claimed and desired to be secured by Letters Patent is:

A window for a ship deck bulkhead and roof, each having an opening providing respectively for outward horizontal and vertical skyward vision, said openings being adjacent and in alignment, said window comprising a fixed lower frame for said bulkhead opening extending downwardly therebelow at the inboard side of said bulkhead; a lower sash slidably engaged by said frame, in closed position when raised adjacent said bulkhead opening, and in open position when lowered opposite said bulkhead; a fixed upper frame for said roof opening having its bottom adjacent the top of said lower frame and extending in an inboard direction therefrom; an upper sash hinged at its lower edge to the top edge of said lower sash, swingable about said hinge in an inboard direction to a position abreast of said lower sash whereby both said sashes will be opposite said bulkhead below said lower opening when said lower sash is in lowered window-open position, providing a clear view through said openings horizontally and skyward, said upper sash being swingable against said upper frame to closed position when said lower sash is in its said closed position; and releasable means for holding said sashes closed.

DAVID R. LEAHY.
